GRINDING MACHINE

Application filed April 10, 1928. Serial No. 268,847.

This invention appertains to improvements in grinding machines generally, and more particularly to a type of such machines adapted for use in regrinding scored and worn 5 engine cylinders.

An object of the invention is to provide a machine of the class set forth, which will be comparatively simple and inexpensive in construction and manufacture, but extremely 10 durable, accurate and efficient in operation.

Another object of the invention is to provide a machine as hereinbefore characterized, which will embody a novel form of means whereby the grinding element and the holder 15 thereof may be readily and easily adjusted to proper size for the regrinding of engine cylinders of varying bore diameters.

A further object of the invention is to provide a grinding machine as hereinbefore mentioned, which also embodies a novel means for removably attaching the abrasive or grinding material to the holder therefor, and which readily permits of the respacing of the material about the holder in a manner 25 that successive intermediate active portions of the same will be brought into operative position and the entire surface may thereby be fully utilized.

With the foregoing and other equally important objects in view, the invention resides in the certain new and useful combination, construction and arrangement of parts as will be hereinafter more fully described, set forth in the appended claims, and illustrated 35 in the accompanying drawing, in which:

Figure 1 is a vertical section through a practical embodiment of the device as it appears in operative relation to an engine cylinder.

Figure 2 is a horizontal section taken on the line 2—2 of Figure 1, and

Figure 3 is a fragmentary perspective view of the abrading element of the device.

Referring to the drawing, wherein like characters of reference designate corresponding parts in the several views thereof, the embodiment of the invention, as shown therein by way of example, is constituted in an arbor or shaft 10, which preferably has its 45 lower end screw threaded, as at 11, to receive

thereon a lock nut or the like 12, on which is supported a lower circular member or disc 13.

Supported on the upper side of this member or disc 13 is an annular member or washer 14, which has its peripheral edge upwardly 55 bevelled, as at 15. Rising from the upper side of the member or washer 14 is a spacing sleeve 16, which supports a second circular member or disc 17. Mounted on the upper side of this latter member or disc 17 is a sec- 60 ond annular member or washer 18 also having its peripheral edge upwardly bevelled, as at 19.

The arbor or shaft 10 is formed to provide an annular groove 20 at a point in the plane 65 of the upper side of the member or washer 18 to receive therein a split member or washer 21 against which the several parts below the same are clamped when the lock nut 11 is tightened upwardly on the lower threaded 70 end 11 of the arbor or shaft, and against the lower side of the bottom member or disc 13.

Both of the circular members or discs 13 and 17 are each provided with a plurality of equidistantly spaced and radially extending 75 slots 22, which open outwardly of the peripheral edges of the same, the several slots of one of the members or discs being aligned with those of the other thereof.

Mounted in the complementary slots 22 of the members or discs 13 and 17 are vertically elongated members or plates 23, which have the inner and lower corner portions thereof cut away to provide angularly disposed edge portions 24, which seat against 80 the bevelled edge portion 15 of the lower annular member or washer 14. Similarly, the inner edge portions of these members or plates 23, at or immediately adjacent the upper ends thereof, are cutaway or notched in a manner 85 to provide angularly disposed edge portions 24', which, in turn, seat against the bevelled edge 19 of the upper annular member or washer 18. The several members or plates 23 are tensioned inwardly of the slots 22 by 90 resilient members or springs 25, which have their lower ends attached to the upper side of the bottom circular member or plate 13, and each of their upper ends to one side of 95 the members or plates 23, as by means of the 100

ends thereof being angularly bent into engagement in suitable openings formed in the members or plates substantially as shown. To increase the natural resiliency of the members or springs 25, the intermediate portions 5 thereof, as at 26, may be bent to circular or other desired form for the purpose.

Supported on the upper end edges of the several members or plates 23 is a circular member or disc 27, which has its upper side contacted by a circular series of ball bearings or the like 28 carried in a raceway formed in the lower side of an adjusting member or nut 29 arranged in threaded engagement with 10 the upwardly projecting portion of the arbor or shaft 10, which portion of the latter is complementally screw threaded to within but a relatively short distance below its extreme upper end. A universal joint or coupling 15 30 is secured on the extreme upper end of the arbor or shaft 10 and connects with the lower end of a power shaft 31. Rising from the adjusting member or nut 29 is a cylindrical member or sleeve 32, by means of which 20 25 the operation of the member or nut may be facilitated.

A strip of abrasive or grinding material 33, such as emery cloth or the like, is provided, and the same is preferably of a width 30 substantially equal to the length of the members or plates 23, and of a length to be encircled about the outer side edges of the latter with its opposite end edges disposed in closely spaced relation and in a manner to 35 prevent the overlapping thereof. One end edge of the abrasive strip 33 is preferably provided with a metal attaching member 34, which is formed with an angularly disposed portion 35 to be engaged in any one pair of 40 45 complementary slots 36 formed radially inward of the peripheral edges of the members or discs 13 and 17.

In the use of the device as thus constructed and arranged, and with a strip of the abrasive or grinding material 33 encircled about the periphery of the device, as defined by the outer side edges of the vertical members or plates 23, substantially as shown in Figure 2, the lower end thereof will be inserted 50 downwardly of the bore of an engine cylinder A. When operatively positioned, the abrasive or grinding material 33 will be smoothly and uniformly pressed against the cylinder wall by the outward pressure of the 55 radially movable vertical members or plates 23. With the device properly supported in position, power applied to the upper shaft 31 will be transmitted to the arbor or shaft 10 through the medium of the coupling 30, when 60 the abrasive or grinding fabric 33 will be rotated against the cylinder wall in an accurate and effective manner.

To adjust the device for use in cylinders of various diameters, the adjusting nut 29 65 will be either heightened or loosened on the

arbor or shaft 10 with respect to the bearing plate 27. When tightened downwardly of the upper threaded portion of the arbor or shaft 10, the nut 29 forces the bearing plate 27 downwardly on the upper ends of the vertical plates 23, and the latter are forced outwardly of the radial slots 22 in the circular members or plates 13 and 17, by the cam action of the bevelled edges of the lower and upper washers 14 and 18 against the complementary angularly inclined edge portions 24 and 24' at the lower and upper ends of the inner edges of the plates 23, and against the tension of the resilient members or springs 25, and, conversely, by loosening up on the nut 29, the latter act to withdraw the vertical plates 23 inwardly of the slots 22.

To afford a substantial bearing surface to the outer side edges of the vertical members or plates 23, the same are preferably formed to provide angular offset portions or flanges 23', substantially as shown, and which are also preferably disposed at the trailing sides of the plates 23 with respect to the direction of rotation of the device. By moving the attachment element progressively from one pair of complementary slots or notches 36 in the peripheral edges of the circular members or plates 13 and 17, fresh portions of the abrasive surface of the strip 33 may be presented to the work at the outer side edges of the vertical plates 23 whenever necessary or desired, and until the entire surface has been used. The attaching member 34 may be detachably connected at an end edge of the strip of abrasive or grinding material, so as to be removable for use on replacement strips thereof.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

Having thus fully described the invention, what is claimed is:

1. In a device of the class described, an arbor, a pair of spaced flat circular disks carried by said arbor, a plurality of circumferentially spaced members extending edgewise between said disks and movable radially thereof, an abrasive element encircling the outer side edges of said members, and means for adjusting said members relatively to said arbor and said disks to vary the diameter of said abrasive element correspondingly for grinding engine cylinders and the like of different sizes.

2. In a device of the class described, an arbor, a pair of spaced circular disks carried by said arbor, a plurality of circumferentially spaced members extending between said disks

- and movable radially thereof, means for normally sustaining said members in contracted relation about said arbor, an abrasive element encircling the outer side edges of said members, and means for adjusting said members relatively to said arbor and said disks to vary the diameter of said abrasive element correspondingly for grinding engine cylinders and the like of different sizes.
3. In a device of the class described, an arbor, a pair of spaced circular disks carried by said arbor, a plurality of circumferentially spaced members extending between said disks and movable radially thereof, resilient means for normally sustaining said members in contracted relation about said arbor, an abrasive element encircling the outer side edges of said members, and means for adjusting said members relatively to said arbor and said disks to vary the diameter of said abrasive element correspondingly for grinding engine cylinders and the like of different sizes.
4. In a device of the class described, an arbor, a pair of spaced circular disks carried by said arbor, a plurality of circumferentially spaced members extending between said disks and movable radially thereof, resilient means cooperative with each of the said members for normally sustaining the same in similarly contracted relation about said arbor, an abrasive element encircling the outer side edges of said members, and means for adjusting said members relatively to said arbor and said disks to vary the diameter of said abrasive element correspondingly for grinding engine cylinders and the like of different sizes.
5. In a device of the class described, an arbor, circular discs mounted on said arbor in spaced relation and having a plurality of aligned radially disposed slots opening outwardly of the peripheral edges thereof, a movable member disposed in each pair of the said aligned slots, an abrasive element encircling the outer side edges of said movable members, and means carried on said arbor for adjusting said movable members radially of said discs to vary the diameter of said abrasive element correspondingly for grinding engine cylinders of different sizes.
6. In a device of the class described, a power driven arbor, circular discs mounted on said arbor in spaced relation and having a plurality of aligned radially disposed slots opening outwardly of the peripheral edges thereof, means secured at the lower side of said arbor for supporting said discs in position, a movable member disposed in each pair of the said aligned slots, an abrasive element encircling the outer side edges of said movable members, and means carried on said arbor for adjusting said movable members radially of said discs to vary the diameter of said abrasive element correspondingly for
- grinding engine cylinders of different sizes.
7. In a device of the class described, an arbor, circular discs mounted on said arbor in spaced relation and having a plurality of aligned radially disposed slots opening outwardly of the peripheral edges thereof, a movable member disposed in each pair of the said aligned slots, an abrasive element encircling the outer side edges of said movable members, means for attaching said abrasive element to said discs, and means carried on said arbor for adjusting said movable members radially of said discs to vary the diameter of said abrasive element correspondingly for grinding engine cylinders of different sizes.
8. In a device of the class described, an arbor, circular discs mounted on said arbor in spaced relation and having a plurality of aligned radially disposed slots opening outwardly of the peripheral edges thereof, a movable member disposed in each pair of the said aligned slots, an abrasive element encircling the outer side edges of said movable members, means for attaching said abrasive element to said discs at one end only, and means carried on said arbor for adjusting said movable members radially of said discs to vary the diameter of said abrasive element correspondingly for grinding engine cylinders of different sizes.
9. In a device of the class described, an arbor, circular discs mounted on said arbor in spaced relation and having a plurality of aligned radially disposed slots opening outwardly of the peripheral edges thereof, a movable member disposed in each pair of the said aligned slots, an abrasive element encircling the outer side edges of said movable members, means for removably attaching said abrasive elements to said discs at one end only, and means carried on said arbor for adjusting said movable members radially of said discs to vary the diameter of said abrasive element correspondingly for grinding engine cylinders of different sizes.
10. In a device of the class described, a power driven arbor, circular discs loosely mounted on said arbor, a sleeve on said arbor for spacing said discs apart, a lock nut threaded on the lower end of said arbor for supporting said discs and said sleeve in position, members movable in pairs of aligned slots formed radially of said discs, an abrasive element encircling the outer sides of said movable members, and means carried by said bar for adjusting said movable members radially of said discs to vary the diameter of said abrasive element correspondingly for grinding engine cylinders of different sizes.
11. In a device of the class described, a power driven arbor, circular discs loosely mounted on said arbor, a sleeve on said arbor for spacing said discs apart, a lock nut

threaded on the lower end of said arbor for supporting said discs and said sleeve in position, members movable in pairs of aligned slots formed radially of said discs, an abrasive element encircling the outer sides of said movable members, bevelled annular members carried by said arbor and cooperative with similarly bevelled portions formed with said movable members, and a movable means carried by said arbor for actuating said movable members relative to said annular members, whereby the same are adjusted radially of said discs to vary the diameter of said abrasive element for grinding engine cylinders of different sizes.

12. In a device of the class described, a power driven arbor, circular disks mounted on said arbor, a sleeve on said arbor for spacing said disks apart, a lock nut threaded on the lower end of said arbor for supporting said disks and said sleeve in position, members movable in pairs of aligned slots formed radially of said disks, resilient means carried by one of said disks and cooperative with each of the said members for normally sustaining the same in similarly contracted relation within said slots, an abrasive element encircling the outer sides of said movable members, bevelled annular members carried by said arbor and cooperative with similarly bevelled portions formed with said movable members, and a movable means carried by said arbor for actuating said movable members relative to said annular members, whereby the same are adjusted radially of said disks to vary the diameter of said abrasive element for grinding engine cylinders of different sizes.

13. In a device of the class described, an arbor, a pair of spaced circular disks carried by said arbor, a plurality of circumferentially spaced members extending lengthwise between said disks and movable radial thereof, an abrasive element encircling the outer side edges of said members, said arbor being screw threaded outwardly from the opposite outer sides of said disks, a lock nut engaged on one of the screw threaded portions of said arbor and disposed in abutting relation with the adjacent of said disks, means for moving said members relative to said arbor and said disks to vary the diameter of said abrasive element correspondingly for grinding engine cylinders and the like of different sizes, and means engageable with the outer of the threaded portions of said arbor for actuating said last named means.

ALVIN R. BERCK.
